Primary Examiner — Marianne Pandozzi(74) *Attorney, Agent, or Firm* — Law Office of Mark Brown, LLC; Mark E. Brown; Christopher M. DeBacker(57) **CLAIM**

The ornamental design for a two-compartment beverage vessel with split top cover, as shown and described.

DESCRIPTION

FIG. 1 is a perspective view of a two-compartment beverage vessel with split top cover;

FIG. 2 is a front elevational view of a two-compartment beverage vessel with split top cover, the rear elevational view being a mirror image thereof;

FIG. 3 is a right side elevational view of a two-compartment beverage vessel with split top cover, the left side elevational view being a mirror image thereof;

FIG. 4 is a top plan view thereof; and,

FIG. 5 is a bottom plan view thereof.
